P. P. Sprague

United States Patent Office.

JOHN S. HYDE, OF PENTWATER, MICHIGAN.

Letters Patent No. 96,811, dated November 16, 1869.

IMPROVEMENT IN LATH-MILLS.

The Schedule referred to in these Letters Patent and making part of the same.

To whom it may concern:

Be it known that I, JOHN S. HYDE, of Pentwater, in the county of Oceana, and State of Michigan, have invented a new and useful Improvement in Gang-Lath Mills; and I do declare that the following is a true and accurate description thereof, reference being had to the accompanying drawings, and to the letters of reference marked thereon, and being a part of this specification.

Figure 1 is a front view of my apparatus.

Figure 2 is a top view of the same.

The same letters refer to like parts in each figure.

This invention relates to machines for sawing laths, and consists in an improved form of roller, as will be fully described hereinafter.

In order to accomplish this end, I construct a machine, whose various parts I will now name.

A is a saw-frame, of any suitable construction, surmounted by the yokes O, to which are attached proper arbors for the saw-mandrel D, and the roller-shafts E and F.

The mandrel D is provided with a gang of saws, secured in the usual way at or near the outer end of the mandrel.

The saws are designated by x.

The pulley C is fastened upon said mandrel, at or near its centre, and when properly connected by a belt, gives motion to the whole of the mechanism of the machine.

On the mandrel, and near the pulley C, is rigidly fastened the pulley J, which, being connected to countershaft H, by belt 6 and pulley I, imparts motion to the same.

At the outer end of the countershaft H there is attached a proper pulley, giving motion and same direction to the feed-roller shafts E, by means of the pulleys K and belt 8.

The lower rollers F are driven in an opposite direction by means of pinions G, meshing into corresponding pinions attached to the shafts which carry the lower rollers.

The saws B are located, as heretofore described, on the

mandrel D, midway between the feed-rollers E and F, and in position to saw the bolt or plank as it passes through by the feed-rollers heretofore described.

The rollers E and F are provided with separating collars 1, 1, 1, dividing the laths after being sawed, and securing a parallel position of the same until the laths pass from the saws and rollers, and are delivered upon the inclined way U, and are deposited back of the machine, as may be desired.

R is a bar upon the top of the way U, which divides the lath from the bolt or plank, the lath being disposed of, as hereinbefore described, while the bolt or plank falls upon rollers L, when, by their motion, the bolt or plank is returned to the operator, the rollers P¹ and P².

Motion is given to the rollers L by pulleys 2, belt 7, and pulley 3, on countershaft H.

The curved spring M rests at each end on boxes pivoted on top of the shafts E, near the yoke O, and is secured at its centre by the screw X passing through a proper ear attached to the yoke O, thereby securing an adjustability to the upper feed-rollers, according to the thickness of the bolt to be sawed.

T is a platform or table, from which to feed the machine, and attached thereto is the wall S, acting as a guide.

V are stops at the ends of the machine, to prevent the bolts from being driven out of the ends of the machine, and supporting-bar Q serves for a bridge-tree to sustain the outer ends of the rollers L and F, while their opposite ends are sustained by the frame.

5, 4, and 9, are intermediate tightening-pulleys for the different belts.

What I claim as my invention, and desire to secure by Letters Patent, is—

The feed-rollers E, constructed as described, when used for the purpose of separating the laths, as set forth.

JOHN S. HYDE.
